UNITED STATES PATENT OFFICE.

WILLIAM G. FROST, OF BROAD RIPPLE, INDIANA.

RENEWABLE-FRONT WASHBOARD.

No. 879,761.

Specification of Letters Patent.

Patented Feb. 18, 1908.

Application filed October 13, 1906. Serial No. 338,706.

To all whom it may concern:

Be it known that I, WILLIAM G. FROST, a citizen of the United States, residing at Broad Ripple, in the county of Marion and State of Indiana, have invented new and useful Improvements in Renewable - Front Washboards; and I do declare the following to be a full, clear, and exact description of the invention, reference being had to the accompanying drawings, and to the letters and figures of reference marked thereon, which form a part of this specification.

This invention relates to the class of washboards that are adapted to permit of the removal of the rubbing plate thereof when worn out, and the insertion of a new one in lieu thereof.

Objects of the invention are to provide a washboard of improved construction in which a simple and cheap form of rubbing plate may be employed as a removable part thereof, so as to be cheaply renewed; to provide a washboard adapted to permit of the removal or insertion of a rubbing plate by unskilled persons without the use of special tools, and to provide a washboard of the above-mentioned character which may be simply and cheaply constructed and be durable and economical in use.

With the above-mentioned and minor objects in view the invention consists in a washboard comprising a frame having bearings, a back and a rubbing plate fitted together and supported removably on the bearings, and a novel locking key securing the back and the rubbing plate on the bearings; and, the invention consists further in the novel construction and combinations of parts or elements as hereinafter particularly described and claimed.

Referring to the drawings, in which similar reference characters designate corresponding elements or features, Figure 1 is a perspective view of a washboard constructed substantially in accordance with the invention; Fig. 2, a rear elevation thereof; Fig. 3, a sectional view thereof on the line A A in Fig. 2; Fig. 4, a sectional view of the frame of the washboard on the line A A in Fig. 2; Fig. 5, a sectional view of the complete washboard on the line B B in Fig. 2; Fig. 6, a perspective view of the locking key; Fig. 7, a rear elevation of the washboard slightly modified so as to change the relative position of the locking key; Fig. 8, a sectional view on the line C C

in Fig. 7; Fig. 9, a sectional view of the frame on the line C C in Fig. 7; Fig. 10, a sectional view of the back and the rubbing plate respectively, separated, as on the line C C in Fig. 7; Fig. 11, a front elevation of the washboard slightly modified so that the rubbing plate is inserted into the front of the frame instead of the back as shown in the preceding figures; Fig. 12, a rear elevation of the washboard shown in Fig. 11; Fig. 13, a sectional view on the line D D in Fig. 12; Fig. 14, a sectional view of the frame on the line D D in Fig. 12; Fig. 15, a sectional view of the frame alone on the line E E in Fig. 12; Fig. 16, a front elevation of a slightly modified form in which the position of the locking key is changed from that shown in Figs. 11 to 15; Fig. 17, a sectional view on the line F F in Fig. 16; Fig. 18, a sectional view of the frame on the line F F in Fig. 16; and, Fig. 19 is a sectional view of the frame alone on the line G G in Fig. 16 looking upward.

In construction the improved washboard comprises a frame that consists essentially of two upright side bars, the lower ends of which serve as legs for supporting the washboard in a tub when in use, two cross bars secured suitably to the side bars so as to form therewith a rigid support for holding the rubbing plate and the back therefor, and a soap box formed of the side bars, one of the cross bars, and a bottom and a head-piece secured suitably to the side bars, the side bars and the cross bars being adapted to be slightly modified, so that the rubbing plate may be inserted into the frame and secured therein in various ways, as may be desired, without sacrificing any of the advantages of the invention. The modifications in the frame do not require any modification in either the rubbing plate, the back therefor, or the locking key.

In Figs. 1 to 6 inclusive the preferred construction is shown in which *a* and *b* are the side bars; *c* the head piece on the upper ends of the side-bars; *d*, the uppermost cross-bar extending from one side-bar to the other somewhat near the head-piece *c* and having a holding lip *d'* at the rear thereof extending towards the lower end of the frame; *e*, the lowermost cross bar extending from one side bar to the other at a suitable distance from the cross bar *d*; and, *f*, the soap box bottom at the back of the frame extending from the

head-piece *c* to the cross-bar *d* and from one side-bar to the other one. Each side-bar is provided at the front thereof with a guide bearing *g* extending approximately from the cross-bar *d* to the cross-bar *e* and one bearing towards the other, for supporting the rubbing plate and its back, the bearings being formed preferably by rabbeting the inner sides of the side-bars, as shown. The 10 side-bars have each a lug *h* at the rear part thereof opposite to the cross-bar *e* for holding the locking key. The rubbing plate *i* rests on the bearings *g* against the cross-bar *e*, and the back *j* rests against the back of the 15 rubbing plate under the lip *d'* of the cross-bar *d* and against the cross-bar *e*. The key *k* extends across the rear or outer side of the back *j* between it and the lugs *h*, the key having preferably a wedge-shape, the lower edge 20 being of less thickness than the upper edge 21 thereof. The rubbing plate *i* has flanges 22 and 23 to embrace the ends of the back *j*, the latter preferably having stiffening cleats *l* and *m* on the back thereof, 25 which however, may be dispensed with if the back be made stiff enough without them.

In Figs. 7, 8 and 9 the uppermost cross-bar *n* is spaced apart from the bottom *f*, and the key *k* is inserted between the cross-bar 30 and the bottom of the soap-box to hold the rubbing plate and its back against the bearings *g*, the lowermost cross-bar *o* having a holding lip *o'* adapted to hold the lower ends of the rubbing plate *i* and its back *j* against the bearings *g*.

Figs. 11 to 15 inclusive show the frame modified to permit of the withdrawal of the rubbing plate from the front of the frame, which comprises side-bars *p* and *q* having 40 each a bearing *r* at the rear side thereof for supporting the back *j* and the plate *i*, the uppermost cross-bar *s* having a holding lip *s'* for holding the upper ends of the rubbing plate and its back against the bearings *r*, the 45 lowermost cross-bar *t* having a lip *t'* to support the lower ends of the plate and its back, each side-bar being provided with a lug *u* to be engaged by the key *k* which secures the plate and its back in the frame.

50 In Figs. 16 to 19 inclusive the side-bars *v* and *w* are provided with the bearings *r*, and a lower cross-bar *x* is provided having a groove 24 in its upper side to receive the lower ends of the rubbing plate *i* and its back *j*, there 55 being a plain upper cross-bar *y* near the lower edge of the bottom *f*, and the side-bars *v* and *w* have channels 25 and 25^a therein in which

the key *k* is inserted to lock the upper ends of the plate *i* and its back *j*.

When it becomes desirable to renew the 60 rubbing plate *i* it will be necessary to remove the locking key *k* from its seats, and then the rubbing plate and its back may be instantly removed from the frame, after which a new plate may be readily inserted and keyed in 65 the frame.

Having thus described the invention, what is claimed as new is—

1. A washboard comprising a frame with two side bars, a rubbing plate in the frame, 70 and a wedge-shaped locking key comprising a bar having one of its longer sides inclined to the plane of the opposite longer side of the bar so that one longer edge is thinner than the other longer edge of the bar, the key 75 extending from one to the other side bar and having its ends inserted removably in the side bars and normally locking the rubbing plate in the frame.

2. A washboard comprising a frame with 80 side bars, bearings on the side bars, and a lower cross-bar; lugs on the side bars opposite to the cross-bar, a rubbing plate in the frame, and a locking key extending across the rubbing plate from one side bar to another 85 side bar and having its ends inserted between the lugs and the lower cross bar.

3. The herein-described improvement in washboards, comprising two side bars, bearings on the fronts of the side bars, an upper 90 cross bar with a lip opposed to the bearings, a lower cross bar, lugs on the side bars opposite to the lower cross bar, a rubbing plate on the bearings, a back board on the rubbing plate between it and the lip, and a locking key 95 extending against the back board from one side bar to the other side bar unattached to the back board and engaging the lugs on the side bars, substantially as set forth.

4. In a washboard, the combination with a 100 frame having two side bars and two cross bars, a rubbing plate, and a back board in the frame, of a wedge-shaped locking key engaging the two side bars and one of the cross bars and locking the rubbing plate and the back board removably in the frame, said key being removable laterally away from the cross bar, substantially as set forth.

In testimony whereof, I affix my signature in presence of two witnesses.

WILLIAM G. FROST.
